UNITED STATES PATENT OFFICE.

RUDOLPH DE BOER, OF GRAND RAPIDS, MICHIGAN.

DESIGN FOR A WALL POCKET OR SIMILAR ARTICLE.

Application filed February 10, 1927. Serial No. 20,674. Term of patent 7 years.

To all whom it may concern:

Be it known that I, RUDOLPH DE BOER, a citizen of the United States, residing at No. 331 Ionia Avenue NW., Grand Rapids, in the county of Kent and State of Michigan, have invented a new, original, and ornamental Design for Wall Pocket or Similar Article, of which the following is a specification, reference being had to the accompanying drawing, forming a part thereof, in which:—

I claim:

The ornamental design for a wall pocket or similar article substantially as shown.

RUDOLPH DE BOER.
